UNITED STATES PATENT OFFICE.

HENRY S. DOSH, OF BALTIMORE, MARYLAND.

BAKER'S PAN OR TRAY.

SPECIFICATION forming part of Letters Patent No. 340,492, dated April 20, 1866.

Application filed June 12, 1885. Serial No. 168,486. (No model.)

To all whom it may concern:

Be it known that I, HENRY S. DOSH, of the city of Baltimore, and State of Maryland, have invented certain Improvements in Bakers' Pans or Trays, of which the following is a specification.

My invention consists in an improved construction of the frame of the tray or pan, as will hereinafter fully appear.

10 In the accompanying drawings, forming a part hereof, Figures I and II are respectively a top and an under side view of the improved pan. Fig. III is a longitudinal section of the pan before the supporting-frame is secured in place. Fig. IV is a longitudinal section taken on the dotted line $x x$, Fig. I. Fig. V illustrates a modified construction of the pan.

Referring to Figs. I, II, III, and IV, A is the sheet of iron forming the main portion of 20 the pan or tray, and B the frame. The frame consists of the lower continuous flange, a , and the upper broken one, b . These flanges, before the frame is secured to the plate A, form

a right angle, as shown in Fig. III, and after the sheet, the edge of which is preferably 25 turned over, is placed in the frame the broken flange b is crimped upon the plate, as shown in Figs. IV and V.

I have alluded to the flange b as broken. By this I mean that the said flange is not continuous, but notched at the corners of the frame, so that the four sections may be separately turned over, and without being buckled.

I claim as my invention—

In a baker's pan or tray, the combination of 35 the sheet A and the frame B, which consists of the connected flanges a and b , the former being in one continuous piece, and the latter separated or notched at the corners, the two flanges engaging the sheet on opposite sides, 40 substantially as specified.

HENRY S. DOSH.
